UNITED STATES PATENT OFFICE.

WILLIAM HENRY BEALE, OF WELLINGTON, NEW ZEALAND.

CIRCULAR-FASHIONING KNITTING-MACHINE USING DOUBLE-ENDED LATCH-NEEDLES.

1,073,885.

Specification of Letters Patent. Patented Sept. 23, 1913.

Application filed August 8, 1910. Serial No. 576,037.

To all whom it may concern:

Be it known that I, WILLIAM HENRY BEALE, of Vivian street, in the city of Wellington and Dominion of New Zealand, have invented a new and useful Circular-Fashioning Knitting-Machine Using Double-Ended Latch-Needles, of which the following is a specification.

This invention relates to a knitting machine of the circular type for the production of tubular seamless hosiery and has for its primary object the provision of means which will enable the machine to manufacture socks or stockings more expeditiously and with a minimum amount of wear and tear as compared with the machines at present in use.

A leading feature of the invention is its entire simplicity of construction and consequent small cost of production which will render the machine salable to small manufacturers as well as others.

The invention is such that it commences its manufacture at the top of the sock or stocking and forms the leg with a full complement of needles by a circular or rotary action till it reaches the heel and toe which formation is effected by knitting the same upon approximately one half of the full complement of needles by a reciprocating action and reducing the number of needles in action at each course until a minimum number of needles remain then re-introducing them again into action when a pouch or pocket for the heel and toe is formed. The operation of narrowing and widening is carried out automatically by the mechanism upon the manipulation of certain devices arranged conveniently upon the outside of the machine while the action of transferring from rib to plain knitting and vice versa is effected automatically by the machine upon the manipulation of certain levers on the outside of the machine.

In carrying these objects into effect the construction comprises briefly two specially constructed needle cylinders disposed endwise relatively to each other in a vertical position, the upper cylinder being held in position by an arched member or bridge connected to the body of the machine while the lower cylinder is disposed to a slight vertical movement which serves to vary the tension of the machine.

The lower needle-cylinder which is provided with webholders and needle jacks of

special construction is contained within a circular member to be termed the body portion of the machine, which latter is provided with special cams and needle-races and is revolvably mounted within a circular box to be called the body-holder, the lower portion of which forms a bearing for the lower cylinder while a cam box provided with special cams and comprising a semi-circular shaped shell which partly encircles the lower cylinder is attached to the body and rotates around the cylinder when the machine is set in motion.

The upper cylinder which is provided with needle-jacks of special construction and is used for doing ribbing work is contained within a circular cam-box provided with all the necessary appliances such as the various kinds of cam-devices and needle-races to be afterward referred to, while the inside of the cylinder is provided with an adjustable tension ring which projects beyond the lower end of the cylinder and is disposed to a slight vertical movement which serves to alter the tension of the ribbing work by varying the distance between the upper and lower cylinders.

The invention, of which the foregoing is simply a rough outline of its construction, will now be fully described and explained with reference to the accompanying sheets of drawings in which:

Figure 1.— is a front elevation of the machine showing the outside of the lower cam-box. Fig. 2.— is a vertical sectional view of the machine. Figs. 3 and 4.— are respectively outside and inside views of one half of the upper cam-box, Figs. 5 and 6.— are respectively outside and inside views of the other half of the upper cam-box, Fig. 7.— is a view of the inside of the lower cam-box showing the means for "narrowing" and "widening" to form the heel and toe, Fig. 8.— is a view of the body of the machine with the arched member broken away for convenience, Fig. 9.— is a view of the lower needle-cylinder on a reduced scale, Fig. 10.— is a side view of one of the web-holders, Figs. 11, 12 and 13.— are detail views of parts to be afterward referred to, Figs. 14 to 19.— are side views of the needle-jacks employed in the machine, Figs. 20 and 21.— are cross sectional views of parts of the lower and upper needle-cylinders respectively, showing the arrangement of needle-jacks for knitting a plain sock

with a "one-and-one" rib top, Fig. 22.— is a detail view of a portion of the body of the machine, Fig. 23.— is a sectional view of same along the line A—B, Figs. 24 and 5 25.— are detail views of a portion of the machine showing the means employed for transferring the lower-cylinder-transfer-needles to the upper cylinder, Fig. 26 is a development of the inner surface of the 10 lower cam-box; Fig. 27 is a perspective view of a portion of the lower cam-box; Fig. 28 is a vertical section through a portion of the lower cam-box; and Fig. 29 is a plan view of the curved lever carrying certain cams of 15 the lower cam-box...

In carrying out this invention 1 is the body-holder comprising a circular shell or box having an outwardly extending lug 2 from its periphery which serves to support 20 the holder upon a bench or such like 3, and a hanging member or lug 4 which serves to provide a bearing for the driving spindle 5 of the machine. The body-holder 1 is of sufficient depth to provide a bearing surface 25 for the lower needle cylinder 6 which is adapted to fit within the holder so as to be free to move longitudinally therein. The body-holder 1 is provided at its upper end with a ball-bearing-race 7 by means of 30 which the body 8 (Fig. 8) which rests within the holder, may be free to rotate.

The lower cylinder 6 (Fig. 9) comprises three parts viz. an upper portion 6^a which is provided with a longitudinal arrangement 35 of parallel grooves or channels 9 which serve as beds for the needles which are of the ordinary double-ended latch type: a middle portion 6^b, which is provided with a longitudinal arrangement of slots 10 which are 40 alternately situated with the needle-grooves 9 and through which the projections 11 of the web-holders 12 that are contained within the cylinder, are adapted to extend, while the third or lower portion 6^c serves to guide 45 the cylinder in its longitudinal movement within the body-holder, a feather-way 13 being provided which prevents any turning movement of the cylinder.

The top end of the cylinder is provided 50 with an annular cap or plate 14 which is formed with a radial arrangement of slots 15 that correspond with the slots 10 and serve as guides for the top ends of the web-holders 12, while the central opening is used 55 as a hopper for passing the work into a delivery-tube 16 that extends upwardly through the center of the cylinder and is attached to the underside of the plate 14.

Constructed in the middle portion of the 60 cylinder 6 around its periphery, is a recess 17 within which a cam-ring 18 is adapted to travel, the cam 18^a serving to depress the projections 11 of the web-holders 12 and causing the top ends of such to move in an 65 outward direction against the action of

springs 18^b which are tending to normally hold the web-holders in toward the center of the cylinder. A recess 19 is constructed in the cam-ring 18 within which a pin 20 attached to the body, (see Fig. 2.) is adapted to enter and impart a turning movement to the cam-ring when the body is turned, the recess 19 being made sufficiently long to allow a certain amount of play.

The web-holders 12 are formed with a hook 21 at or near the middle of their length which fits upon a wire ring 22 that extends around the top of the slotted member 6^b of the cylinder. By this arrangement the web-holders 12 that are held by separate springs 18^b are entirely independent of each other, with regard to both movement and control.

The cylinder 6 rests upon a fork-shaped-member 23 that is hingedly secured to the body-holder 1 and is held in a variety of different positions by a rod 24 that is attached to the forked-member 23 at its lower end and is supported at its upper end by a short roller or wheel 26 that is securely attached to the rod and rests upon the edge 90 of a cam-disk 27. Any turning movement of the disk 27 will have the effect of raising or lowering the forked-member 23 and consequently the cylinder 6 that is bearing upon it, and has its result in tightening or slackening the work according to whether the cylinder is raised or lowered. Numbers are arranged upon the disk 27 to indicate the position of the different tensions.

The body 8 of the machine which is 100 mounted in bearings upon the top of the body-holder 1 and which comprises a circular shell having an internal diameter large enough to receive the lower cylinder 6 is adapted to be turned in a horizontal plane 105 from the driving spindle 5, through bevel-gearing 28, when the machine is in use.

The upper portion of the body 8 which has a smaller inner diameter than the lower portion thereof and which is adjacent to the 110 periphery of the lower cylinder 6 and forms a bearing surface for the projections or butts of the needle jacks, is formed with an approximately semi-circular-shaped raised portion 29 such raised portion being provided with surfaces 30 and 31 on its inner side that serve to raise the needle jacks onto a higher plane, when the body is turned. Attached to the body 8 at a position diametrically opposite the raised portion 29 is 115 the cam-box 32 comprising an approximately semi-circular-shaped shell (see Fig. 7). Arranged upon the inside of the cam-box 32 are two plates 33 and 34 provided with cam-surfaces 35 and 36 respectively, 120 which serve to impart the necessary movements to the needles for stitching and for reciprocating stitching. Hingedly attached to the ends of these plates 33 and 34 are bridge-pieces 37 and 38 respectively, which 125 130

re adapted to serve as bridges and doors alternately, as will afterward be explained. Arranged between the plates 33 and 34 is a special needle-picking device or needle-lifter 39 (see Figs. 7 and 13) which is adapted to rock to and fro between the plates 33 and 34 as the machine is reciprocated, when forming the heel and toe. The device is provided with a hinge-joint 40 and is pivotally secured upon a pin 41 that extends through a bearing 42 formed in the shell, to the outside of the cam-box where a lever 43 controlled by a spring 44, is secured upon it. The outer extremity of the needle-lifting device is formed with notches 45 extending in from each side in the manner clearly shown in Fig. 7, which serves to receive the leading needle as it passes along the top of the plates 33 and 34 according to which direction the cam-box is moving, when reciprocating. The needle will thus come in contact with the lifting device 39 and will rest within the adjacent notch 45, and as the rotating action of the cam-box continues the pressure of the needle against the lifting device causes the latter to turn upon its pivot and in doing so describes an arc and forces the needle upwardly within the groove of the cylinder till it reaches the highest point of the arc, at which level the needle will be held by the spring-band 46 encircling the needle cylinder 6 and lying within the recess 25. The lifting-device 39 having thus reached the summit of its movement and rid itself of the obstructing needle, it remains for the spring 44, that is attached to the lever 43 and has consequently been drawn out into greater tension, to now exert its pull upon the lever and so cause the lifting device to descend and complete the second portion of its movement, so as to be in position ready to receive the first needle passing after the direction of turning is reversed, and lift it up out of action in the manner before described. Arranged within a slot 47 formed in the shell of the cam-box 32 and extending horizontally across between the plates 33 and 34, in line with the upper surfaces thereof, is a plate 48 of approximately "butterfly" shape (see Fig. 11), which is mounted upon a central pivot or pin 49 so as to be capable of swinging in a horizontal plane and allowing the lifting-device 39 to displace it in order that the latter may place itself in alignment with the end of the upper surfaces of the plates 33 and 34, when in operation. The "butterfly" plate 48 serves to bridge the gap between the plates 33 and 34 in order that the active needles may continue along a horizontal path till they strike the lifting-device 39. The latter is provided with a shoulder 50 (Figs. 7 and 13) which serves as a cam surface in guiding the active needles as they strike against the lifting device, down the

passage 51 between the plates 33 and 32 or the passage 53 between the plates 34 and 32, according to the direction in which the machine is turning, thence they are guided on to the stitch-forming-cam-surfaces 35 or 36 70 when they are carried up through the doors 37 or 38 on to the top of the plates 33 or 34 again as the case may be. Arranged above the needle-lifting-device 39 is a horizontally arranged guide-rail 54 which serves to regulate and limit the lifting movement of the needles. When the required number of needles have thus been rendered inactive in the "narrowing" operation and only a minimum number are now left in action, it now 80 remains for the inactive needles to be knocked down into action again. This reduction of inactive needles or "winding" as it is commonly called, is effected in a similar manner as in certain other machines by 85 causing two needles at a time to be knocked down at each course while only one needle at each course is being thrown up out of action by the needle-lifter before described which still continues in action so long as the 90 machine is doing reciprocating work. Thus it will be seen that the inactive needles will be reduced by one in number at each course the machine takes.

The means devised for effecting the "narrowing" consists of a rocking-device 55 (Figs. 7 and 12) which is arranged above the guide-rail 54 at a point vertically above the needle-lifting-device 39. This rocking-device comprises two parts, an approximately inverted T shaped member 55^a, the shank or stem of which passes up through a sleeve portion 55^b and is controlled by a spring 56 that holds the head of the T shaped member normally against the lower 95 end of the sleeve. The lower end of the T shaped-member 55^a is formed with a recess 57 of a size sufficient to receive two needles while its upper end projects above the top end of the sleeve for a convenient distance 100 as shown. The sleeve portion 55^b is provided or formed with a pin 58 at right angles thereto which passes through a bearing 59 in the shell of the cam-box. The outer end of the pin 58 extends beyond the 105 outer face of the shell and is provided with a lever 60 that is controlled by a spring 61 which holds the lever in such a position that the rocking-device 55 will be normally held out of range of the inactive needles. 110

Above the rocking-device 55 is a horizontal plate 62 so arranged that as the rocking-device is turned upon its pivot the protruding end of the T shaped-member-shank will come in contact with the plate, the action of which will depress the shank and increase the length of the rocking-device, as clearly shown in dotted lines Fig. 7. This extending movement will have the effect of causing the rocking-device to plunge down- 115 120 125 130 135 140

ward so as to press the needles contained within its recess down on to the cam-surface 50 which forwards them into action again.

5 In order to bring the rocking-device 55 into an active position within range of the inactive needles, the position of which is shown in full lines Fig. 7, the end corners of the lever 60 are beveled off so as to provide cam-faces 60^a as clearly shown in Fig. 1.

A plate 63 is slidably secured upon the outside of the cam-box 32 and is formed with a recess or cut-away-portion in its upper edge to provide clearance for the lever 60.

10 15 An outwardly projecting stud or pin 64 is arranged upon the plate at either end of the recess, which, when the plate is moved toward it, will impinge against the cam-face 60^a so as to force the lever up a distance

20 sufficient to turn the rocking-device 55 within easy range of the inactive needles. In order to effect the movement of the plate 63 automatically at every course the machine takes, a lever 65 is provided which is

25 pivotally secured to the cam-box at or near the middle of its length. The upper end of the lever is attached to the plate 63 by means of a pin secured to the plate that extends up through a slotted opening in the lever 65.

30 The lower end of the lever 65 is formed with a lug 66 extending outwardly from its face, which, as the machine is reciprocated will strike against a tappet 67, so as to turn the lever upon its pivot and cause the plate 63

35 to move in the required manner. The tappet 67 is secured upon a pin 68 that extends upwardly through a hole in the flange of the body-holder 1 and is normally held down out of range of the lug 66 by a spring

40 45 69, (as shown in full lines Fig. 1), when the machine is doing circular knitting, and is forced upward within range of the lug 66 (as shown in dotted lines Fig. 1) when the machine is doing reciprocating work, the tappet being held in place by a suitable

50 catch 70 that engages the pin 68. The tappet is prevented from turning when the lug strikes against it by means of the springs 71 that extend outwardly from the tappet in

55 opposite directions, as shown in Fig. 1. Arranged also upon the outside of the cam-box 32 is a stud 72 upon which is mounted a lever 73 in such a manner that the lever will be free to rock thereon and is held in

55 the desired position by means of a suitable clip 74 held in place by a spring 75. Attached to the lower end of the lever are two horn-shaped arms 76 and 77 that extend away from the lever in opposite directions.

60 65 When the upper end of the lever 73 is depressed by knocking it in by hand, the arm 76 is adapted to bear against the end of the lever 43 so as to lock it and consequently the needle-lifting-device 39 in position, when the machine is doing circular knitting.

When the lower end of the lever 73 is depressed the other arm 77 is caused to depress a pin 78 (see Figs. 8, 22 and 23), that is attached to the cam-plate 79 which is hinged within a slot 80 formed in the shell of the body 8. The cam-plate 79 will thus be pushed inward as shown in dotted lines Fig. 23 in which position it is within range of the back needles, and will serve to raise them on to a higher level, when the machine is reciprocating to form the heel and toe. When the lever 73 is again depressed at its upper end at the completion of the heel and toe, the arm 77 is thereby automatically knocked out of engagement with the pin 78 and the cam-plate 79 is returned to its normal inactive position again by means of the spring 81 (Fig. 8).

The upper end of the lever 73 is suitably connected to three different cam-devices viz: a cam-plate 82 (Fig. 7) which serves as a knock-down-cam, by leveling the needles when doing circular knitting; a cam 83 (Fig. 7) which serves to guide the latches of the rib needles on to a horizontally-arranged table 84 (Fig. 7) which holds the latches into the proper position; and a cam 85 which serves to place the rib-needle-latches into position when the selvage is being formed. The lever 73 is so connected to each of these cams 82, 83 and 85 that when the upper end of the lever is depressed by hand, the three cams will be knocked into operation within range of the needles, when circular knitting is to be done, and in a similar manner they are thrown out of action when the lower end of the lever 73 is depressed, when reciprocating knitting is to be done. The cam 82 (see Figs. 27, 28, and 29) is mounted upon one end of a pin P which is adapted to slide through a hole in the cam-box, the other end *p* of the pin being pivoted to the upper end of the lever 73, which enters a slot *c* in the end of the pin. The lever 73 is pivoted in a similar manner to the studs 72 rigidly secured to the cam-box. Upon the top of the cam-box is horizontally arranged a curved lever or plate *d* mounted upon the washer *n* (see also Fig. 7), and is pivoted upon a vertically arranged pin *e*, secured at the top of the cam-box 32 near one end. The plate *d* is so mounted on the pin *e* as to be capable of a small amount of vertical movement, but is pressed downwardly by a spring *f* surrounding the pin *e*. The plate *d* is shaped as shown in dotted lines Fig. 29, and is provided at the end remote from the pivot with the cams 83 and 85. The cam 85 is secured to the end of the lever *d*, while the cam 83 is formed on the plate *g* which is secured to the lever *d* by a screw *h*. Secured upon the top of the cam-box underneath the plate *d* is a plate *i* having the clip 74 which is urged downwardly by the spring 75 anchored at one end to a lug 130

j on the plate *i* and at the other end to a pin *k* secured to the cam-box. A shipper *m* is secured to the lever *73*, as shown in Fig. 27, being broken away in Fig. 28 in order to show other details. It will be observed that in order to move the lever *73* from one side of the pyramidal shaped clip *74* to the other, the engagement of the correspondingly shaped head of the lever *73* with the clip *74* will bend the flexible plate *i* against the action of the spring *75*, so that the plate *i* will press against the plate *d* which will be raised slightly. As the upper end of the lever *73* is pushed toward, or pulled away from, the cam-box, the shipper *m* engages one or the other edge of the lever *d* (see Fig. 27), and partially rotates it about its pivot *76* and so moves all of the cams *82*, *83*, and *85* toward, or away from the interior surface of the cam-box. It will be noted that when the upper end of the lever *73* is moved away from the cam-box, so that its upper end remains on the left of the clip *74*, all the cams lie close against the inner surface 25 of the cam-box.

The table *84* before mentioned is arranged above a feeder *86* for the yarn to pass through, the feeder being adjustable to suit requirements. Attached to the feeder *86* is an adjustable latch-guide *87* (Figs. 1 and 7) of approximately semicircular formation, which serves to place the needle-latches in their required order, when the machine is doing either circular or reciprocating work. A yarn carrier *88* is provided upon the outside of the cam-box *32*, which moves with the cam-box and carries the yarn around the machine.

Referring now to the body *8* of the machine (Figs. 1 and 8) *89* is the arched member or bridge which is formed with a bearing *90* in the middle of its length for an axle *91*, (Fig. 2) that carries an upper or rib-knitting cylinder *92* and circular cam-box *93*, which are situated vertically in line above the lower cylinder and cam-box. The cylinder *92* is likewise arranged with needle-grooves *94* around its periphery to suit the class of work required and these grooves are arranged in line with the grooves of the lower cylinder. The lower ends of the arched member *89* are connected together by an approximately semi-circular-shaped shell *95* which envelops and is attached to the outer periphery of the raised portion *29* of the body *8* before referred to.

Pivotedly mounted upon the outside of the semi-circular shaped shell *95* is a lever *96* (Figs. 8, 24 and 25) which is adapted to operate a transferring device *97*, which, when in use serves to elevate the transfer needles in the lower needle cylinder *6* to the upper needle cylinder *92*. The transferring device *97* which will be more fully referred to later on in the specification when

describing the operation of transferring, is held normally out of range of the needles by means of a spring *98*. The lever *96* while at the same time operating the transferring-device *97*, operates an upthrow-cam *99*, which, when in use (as indicated by full lines Figs. 8, 24 and 25) raises the transfer needles on to the transferring-device *97*.

A suitable doorway or opening *100* (Fig. 8) is constructed in the raised portion *29* of the body *8* and semi-circular-shaped shell *95*, which doorway serves to enable needles to be removed and replaced when occasion requires without having to otherwise disturb the machine. In order that the opening will not interfere with the working of the machine by causing a break in the needle-race, it is provided with a suitable bridge-piece *101* while the block *102* adapted to fit within the doorway serves to keep the needles in place within the grooves of the cylinder, a suitable spring-clip being provided to hold the block in place.

Referring once more to the top cylinder reference being made to Fig. 2 of the drawings, a feature of its construction is the provision made for adjusting it to any desired tension. These means comprise a ring *103* which fits within the lower end of the cylinder in the manner clearly shown in Fig. 2. The ring *103* is adjustable from the top of the axle *91* by means of a screw *104* which is countersunk within the top end of the axle and engages with a shank *105* that extends down through the hollow of the axle *91* where it is attached by means of a screw *106* to the tension ring *103*. The top portion of the axle *91* is inclosed by a collar *107* which rests upon the top of the bridge *89*. The collar *107* is connected to the axle by a set-screw *108* which enters a hole in the axle and serves to hold it in place. A plate *109* rests upon the top end of the collar *107* and extending downwardly through the plate is a screw *110* which engages the head of the screw *104*. The latter screw is prevented from moving up and down without preventing it from turning by means of a pin *111* which passes through the axle *91* and enters a groove or channel *112* extending around the periphery of the head of the screw *104*.

Arranged upon the inside face of the upper cam-box *93* is an approximately semi-circular horizontal guide-plate *113* (Figs. 2, 3 and 4) which is adjustable from the outside of the cam-box by means of pins *114* and *115*, which are connected to the guide-plate *113* and extend through slotted openings *114* formed in the shell of the box. The plate is held in its desired position by means of spring-clips *116* and *117* which engage the pins *114* and *115* respectively. The plate *113* serves to guide the needles into their desired position in the manner which will be afterward understood. Constructed

in the inner periphery of the cam-box at the back of the plate 113 is a recess 118 which receives a cam-plate 119 that throws the transfer-needles down on to a top-transferring-device 120 when transferring the needles from the upper to the lower cylinder. The cam-plate 119 is thrown in or out of action from the outside of the box by means of a pin 121 that is attached to the plate and extends through a slot 122 formed in the cam-box, and is held in place by a spring clip 123. Arranged horizontally above the adjustable plate 113 is a fixed guard-rail 124 which serves to guard a downthrow-cam 125 which is operated from the outside of the cam-box by means of a plate 126 that is slidably mounted upon the cam-box and which is connected to the cam 125 by a pin 127 that extends through a slot 128 in the box, the plate being held in place by a spring-clip 129 as shown. The downthrow-cam 125 operates in conjunction with the top-transferring-device 120, and serves to guide the needles into place when in action. Provided also within the inner face of the cam-box 93 are two welting-cams 130 and 131 which operate in conjunction with the guide plate 113, and are hinged at 132 and 133 respectively, to the cam-box, and are adjustable from the outside of the machine by means of pins 134 and 135 that extend through a slotted opening 136 in the box, and are secured to a plate 137 slidably mounted upon the outside of the cam-box. The plate 137 is held in the lower position (as shown in full lines Fig. 6) or in the raised position (as shown in dotted lines Fig. 6) by means of a spring-clip 138. A cam-plate 139 adjustable from the outside of the cam-box by pins 140 and 141 serves to place the needle-latches upon the horizontally arranged table 84 in the lower cam-box 32. Arranged above this cam-plate 139 is another guide-rail 142 which is provided at one end with a door 143 which is adapted to hinge upwardly (as shown in dotted lines) to permit the needles to pass through on to a stitch-cam 144 and to close so as to serve as a bridge and act in conjunction with the welting-cams 130 and 131 before referred to. The stitch-cam 144 is adjustable from the outside of the cam-box by means of a pin 145 and serves to regulate the stitches of the dial-needles, while a suitable helping-cam 146 which is placed between the stitch-cam 144 and the welting-cams 130 and 131, and is adjustable by means of a pin 147, serves to regulate the formation of the loops. A bridge 148 is hinged to the top end of the cam 146 and serves to cover the gap between the cam 146 and the welting-cams aforesaid, so as to guide the needles across. Arranged above the stitch-cam 144 is a guard-cam-plate 149 which serves to keep the needles upon their path.

Secured to the lower edge of the cam-box are guide-plates 150 and 151 (Fig. 4) which serve to guide the needles into their proper position during action. Likewise to the lower cam-box 32, a doorway or opening 152 is formed in the box, which will give access to the top needles, a filling block being provided to keep the needles in place.

Attached to the upright portions of the arched-member 89 before referred to, is a latch-guide-plate 153 and needle jack guide-plate 154 respectively, the former serving to prevent the latches of the cylinder-needles from closing after coming up through the loop, while the latter prevents the back top needle-jacks from engaging the lower needles when the jacks are lifted out of action when setting the machine to form the heel and toe.

Extending down through the top portion of the arched member 89 is a pin 155 which is adapted to engage with the top cam-box so as to serve as a driving-pin when doing ribbing work, and to be held up out of engagement with the top cam-box by a spring 156 when the machine is doing plain knitting.

To set the machine to knit a plain sock with a "one-and-one" rib top, the needle-jacks 203 which are fully illustrated in Figs. 14 to 19, are placed in the needle-cylinders in the following manner, reference being made to Figs. 20 and 21: The lower cylinder 6 (Fig. 20) is provided with a long-butt-transfer-jack (Fig. 15) and short-butt-stationary-jack (Fig. 19) alternately arranged in the grooves of the front half of the cylinder, while a long-butt-transfer-jack (Fig. 14) and a short-butt-stationary-jack (Fig. 18) are alternately arranged in the grooves of the back half of the cylinder. The jacks in the back half of the cylinder are provided with a lower-short-butt as clearly shown, which the lifting-cam 79 (Figs. 22 and 23) engages, when forming the heel and toe. The long butt of the transfer-jacks performs the duties of knitting, transferring and dividing as will be understood later on when the operation is explained. Referring now to the top cylinder 92 (Fig. 21) the arrangement of the jacks is as follows: one-butt-transfer-jack (Fig. 16) then a vacant groove, two-butt-transfer-jack (Fig. 17) then another vacant groove, one-butt-transfer-jack (Fig. 16), a vacant groove, two-butt-transfer-jack (Fig. 17) a vacant groove, and so on all around the cylinder. The top-butt of these jacks serves to knit, transfer, and divide, while the lower-butt is not used at all in doing "one-and-one" rib and only serves to forward the jacks on to the transferring device when the machine is doing any other combination of rib such as "three-and-one," etc.

Having thus explained the arrangement

of the jacks in both cylinders, the operation will now be proceeded with.

The machine is started from the position shown in Fig. 1, with the top end of the lever 73 depressed so as to throw the lifting-cam 79 out of action and to lock the lifting-device 39 in the manner before described, while the cams 82, 83 and 85 (Fig. 7) are thrown into action. The driving-pin 155 is thrown down into engagement with the top cam-box 93 (as shown in Fig. 1.) The machine is then turned till the lower-transferring device 97 is opposite the tappet 67, then the guide-plate 113 in the top cam-box 93 is pulled down into its lower position by the pins 114 and 115. The lever 96 is then thrown over into the full line position so as to throw the lower-transferring-device 97 into action, which also simultaneously brings the upthrow-cam 99 into action. The machine is then turned a little more than one round so as to cause all the transfer-needle-jacks to transfer their needles to the top cylinder. The operation of transferring the needles from the lower cylinder to the upper cylinder, including the action of dividing and separating, is effected by the transferring-device 97 previously mentioned, which has already been thrown into action with the upthrow-cam 99. On reference being made to Figs. 24 and 25 of the drawings, it will be seen that the upthrow-cam 99 operates upon the top of the semi-circular-shaped-raised-portion 29 which forms the race or path for the butts of the jacks to rest upon, at such a distance from the inner periphery thereof, that only the long butts of the transfer-jacks engage therewith, thereby allowing the short butts of the stationary-jacks to pass along the path in the ordinary manner. The transfer-jacks are forced upwardly in their respective grooves by the cam 99 till the butts rest upon the top edge of a plate 97^a. As the turning action is continued the outer end of the butts strike against the inner face 97^b of the device, and are guided by such face so that the top edge of the plate 97^a enters the notch in the butts. The plate 97^a serves as a rail upon which the butts engage, and is eccentrically arranged in respect to the needle-cylinder so that as the turning movement is continued the jacks engaged will be guided at their upper ends by such rail in an outward direction from the cylinder, sufficient clearance being allowed between the cylinder and the body to permit of its being done (as is clearly shown in Fig. 25). It will be readily understood that the action of pulling out the top end of the jacks will cause them to disengage their needles which have meanwhile been forced up a sufficient distance in the respective opposite grooves in the top cylinder, to engage the empty jacks waiting their arrival, which

are held in place by the spring-band 204 encircling the top cylinder in a similar manner to the spring-band 46 on the lower cylinder. The jacks having thus transferred their needles are then guided back into their grooves again by the rail and leveled down on to their horizontal path again by a guide-plate 97^c, (Fig. 8). After the transferring is completed, the upthrow-cam 99 is thrown down out of action by the lever 96, the turning movement of which will release the transferring-device 97 and permit it to swing out of range of the jacks, under action of the spring 98, the moment the last engaged jack has cleared the rail 97^a. 73 75 77 80

The arrangement of the cylinders is now thus: every jack in the top cylinder with a needle engaged, and every alternate jack in the lower cylinder with a needle engaged, the empty lower-cylinder-jacks being in opposite grooves to the needles in the top cylinder. The arrangement of the top cylinder being, a needle in every alternate groove, while the other alternate grooves remain empty to allow the needles that remain in the lower cylinder to enter when the machine is in action. The operation is then continued by throwing the welting-cams 130 and 131 up out of action (as shown in dotted lines Fig. 6). This movement throws the needles in the top cylinder out of action and leads them on to the path formed by the plate 113, guide-rail 142, bridge 143, cams 144 and 146, and they remain on this path till the selvage is formed, the necessary number of rounds 100 being determined by the operator who has regard to the size of work required. The welting-cams 130 and 131 are now thrown down into action (as shown in full lines Fig. 6) after which the "one-and-one" rib top is 105 formed, during which the latch-guide-plate 153 Fig. 1 is serving to hold the latches of the lower cylinder needles in an opened position while the latch-guide 87 (Fig. 7) is also assisting to keep them down. At the 110 same time the cam 83 (Fig. 7) is serving to hold the latches of the top cylinder-needles upon the table 84, while the cam 139 (Fig. 6) is serving to lift them. The table 84 holds the latches in a horizontal position for 115 the feeder 86 to carry the yarn into the hooks of the needles. When the latches drop off the end of the table 84 they are caused to close on the yarn in the hooks so as to form a loop in the usual manner. After the "one-and-one" rib top is formed, the needles in the top cylinder are transferred back again into the lower cylinder by throwing the down-throw-cam 119 (Fig. 4) into action, 120 which will guide the butts of the needle-jacks on to the transferring-device 120 which operates in precisely the same manner as the lower-transferring-device 97, the operation of which has already been fully explained. 125 The needles are thereby passed down into 130

the lower cylinder again where they are received by the empty transfer-jacks, after which the down-throw-cam 119 is thrown out of action again as is also the top cam-box 5 itself by removing the driving-pin 155.

The top cam-box is left in a position with the guide-plate 113 (Fig. 4) at the back of the machine, the plate being lifted up out of action so as to allow the back needles of 10 the lower cylinder to force the jacks in the upper cylinder out of the way when the machine is forming the heel and toe. When this has been done the leg of the work is finished in plain knitting by the lower-cylinder-needles. The machine is then set for 15 forming the heel. This is done by depressing the lower end of the lever 73 so as to cause the cams 82, 83 and 85 (Fig. 7) to be pulled back out of action while the arm 76 20 disengages the lever 43 so as to unlock the needle-lifting-device 39 inside the cam-box. The action also by means of the arm 77 throws the lifting-cam 79 (Figs. 22 and 23) 25 within range of the needles. The machine is then turned so as to cause the lifting-cam 79 to lift up all the needles at the back of the machine out of action so that only approximately one half of the needles remain 30 in action as is customary when forming the heel and toe. This lifting action of the back needles forces the back jacks of the top cylinder up in their grooves so as to allow sufficient clearance for the lower needles.

The position of the machine when ready for 35 reciprocating is thus. The lower cam-box is at the back of the machine, the bridges 37 and 38 (Fig. 7) resting upon the cam-surfaces 31 and 30 respectively so as to form a horizontal path upon which the butts of 40 the needle-jacks rest. The machine is then reciprocated until the heel is formed, the operation of which has already been explained. The lever 73 is then depressed at its upper end so as to again throw the cams 45 82, 83 and 85 (Fig. 7) into action and to throw the lifting-cam 79 (Figs. 22 and 23) out of action. The foot is then formed by the circular knitting and the toe is finally formed by reducing and increasing the 50 number of needles in the same manner as the heel is formed.

I claim:

1. In knitting machines of the class described, the combination with transfer-needle-jacks, having a butt, of means on said butt and operating mechanism for operating therewith, said means and mechanism being constructed and arranged to effect the operations of knitting, dividing and transferring.

2. In knitting machines of the class de-

scribed, the combination of an upper needle-cylinder, a lower needle-cylinder, and means for transferring needles from one cylinder to the other, comprising transfer-needle-jacks provided with butts, said butts having notches on their undersides, a guide-rail for engaging said notches, and a cam arranged to engage the butts and forward them on to said guide-rail, said guide-rail 65 being eccentrically arranged with respect to the needle-cylinders to cause the jacks to disengage the needles.

3. In knitting machines of the class described, the combination of a needle-cylinder, a cam-box surrounding the same, two cam plates arranged within said cam-box, said cam plates having surfaces forming portions of the path for the needle-butts, a device pivoted to the cam-box between 80 the cam plates and arranged to lift the needle up out of range of the cams at each course, a swingingly mounted bridge-piece located between said cam plates and arranged to be operated by said pivoted device, and means for guiding the active needles from said bridge into engagement with one or the other of said cam plates.

4. In a knitting machine of the class described, the combination of an upper needle-cylinder, a frame, an axle supported by the frame, means on said axle for supporting said cylinder, and means for longitudinally adjusting said supporting means relatively to the axle, comprising a screw-controlled device at the top of the axle.

5. In knitting machines of the class herein described, a needle lifter and means for re-introducing the needles which have previously been rendered inactive by the needle-lifter, comprising a device consisting of an approximately inverted T shaped member, a sleeve portion pivotally mounted to the cam-box through which the shank of the T shaped member extends, a spring 105 holding the head of the T shaped member normally against the lower end of the sleeve portion, and a plate secured horizontally to the cam-box against which the top of the shank is adapted to bear when the device is rocked upon its pivot in such a manner as to depress the shank and so increase the reach of the device, substantially as described and shown.

In testimony whereof, I have hereunto set 115 my hand in the presence of the two subscribing witnesses.

WILLIAM HENRY BEALE.

Witnesses:

FRANK HOLDSWORTH,

JOSEPH GODFREY HOLDSWORTH.
